J. H. DENSMORE, OF BOSTON, MASSACHUSETTS, ASSIGNOR TO HIMSELF AND HIRAM FULLER, OF HALLOWELL, MAINE.

Letters Patent No. 80,858, dated August 11, 1868.

IMPROVED CAR-TRUCK.

The Schedule referred to in these Letters Patent and making part of the same.

TO ALL WHOM IT MAY CONCERN:

Be it known that I, J. H. DENSMORE, of Boston, in the county of Suffolk, and State of Massachusetts, have invented new and useful Improvements in Car-Trucks; and I do hereby declare that the following is a full, clear, and exact description thereof, which will enable those skilled in the art to make and use the same, reference being had to the accompanying drawings, forming part of this specification, in which—

Figure 1 is a longitudinal section of the sleeves through line A B, fig. 3.

Figure 2 is a similar section through line C D of fig. 3.

Figure 3 is a cross-section of the sleeves and axles, through the line E F, figs. 1 and 2.

Similar letters of reference indicate corresponding parts.

The object of this invention is to provide a means of preventing accident on railway-trains through the breakage of an axle or axles.

It consists in the provision of axle-sleeves properly affixed to the framework of the truck, and enclosing the whole length of the axles between the wheels, in such a manner that, should the axle of any one pair of wheels become broken, the wheels will still be held in place on the rails, and continue in motion with sufficient steadiness until the train is stopped, thereby preserving the train from accident.

In the drawings, G are the axles, and H the safety-sleeves enclosing them without touching.

The sleeves are affixed to safety-beams f f, which latter are affixed to the main cross-timber, I, of the truck. e are the housing-boxes or journals for the axle-ends.

Figs. 1 and 2 exhibit different forms of the safety-sleeves and the accessory parts.

The sleeve shown at fig. 1 is provided with flanges, a, which enclose the hub-extensions b, which latter are of greater diameter than the eye of the wheel, and the part of the axle fitting within them will be, consequently, larger than that within the eye of the wheel, so that the axle will be more liable to break at that point; but should it, for any reason, break in that vicinity, (as at the point d,) the sleeve, at a, will act as a bearing for the hub-extension b, and thus retain the wheel in a position to run on the rails.

In fig. 2, a more simple and nearly as efficacious form of the sleeve-ends is shown.

In this form the flange j is straight, and its face abutting against the proximate face of the hub of the wheel, serves to retain the wheel in a vertical position when the axle is broken at the point d, as before; but when the axle is broken within the sleeve, it will hold the wheel in the proper position, and with equal firmness as the form of sleeve shown in fig. 1.

The form of sleeve shown in fig. 1 is designed as a new construction, and is not adapted to the axles and wheels already in use; but that shown at fig. 2 may be readily applied to the axles and wheels now in use, for the said sleeve is made in two equal parts, and provided with lateral flanges or lugs, through which screw-bolts are fitted, to hold the said parts firmly together.

The complete sleeve is then affixed to the safety-beams f f by long bolts, l, which are provided with jam-nuts to hold bolts firmly affixed to the safety-beams, while their lower portions play freely through the guide-lugs m of the sleeve.

Springs, k, of metal or rubber, are affixed between the safety-beams and the sleeve, to keep the latter from undue motion; that is to say, to keep it from rising and touching the axle while the wheels are running in their ordinary condition.

The space, h, between the axles and the sleeves, (of both forms of construction,) is for the purpose of allowing a small amount of unavoidable vibration to take place without contact of the sleeves and axles.

The cross-timber I is affixed to the plates or springs J J, which latter are affixed to the journal-boxes e of the truck, and thus the truck is supported, while the axles remain unbroken; but should an axle break, the sleeve furnishes a bearing for the stump of the axle, as will be obvious.

I desire to be understood as not limiting myself to the precise construction of the truck as shown in the drawings, as the same can be variously modified or changed without departing from the principle of my invention.

I claim as new, and desire to secure by Letters Patent—

The construction and arrangement of safety-sleeve H, substantially as shown and described, in combination with the axles and wheels of car or tender-trucks, when the said sleeves are made in two parts and affixed to safety-beams f f, all as set forth.

J. H. DENSMORE.
